UNITED STATES PATENT OFFICE.

PETER M. WEGE, OF YOUNGSTOWN, OHIO, ASSIGNOR TO THE GENERAL FIREPROOFING COMPANY, OF YOUNGSTOWN, OHIO, A CORPORATION OF OHIO.

SHEET-METAL CONSTRUCTION.

No. 839,527.

Specification of Letters Patent.

Patented Dec. 25, 1906.

Application filed June 2, 1906. Serial No. 319,894.

To all whom it may concern:

Be it known that I, PETER M. WEGE, a citizen of the United States, and a resident of Youngstown, Ohio, have invented certain new and useful Improvements in Sheet-Metal Construction, of which the following is a specification, accompanied by drawings.

This invention relates to sheet-metal construction of doors, panels, wardrobe-lockers, and other structures, although the principles of construction may be applied in whatever connection they may be found useful.

The objects of the invention are to improve upon such structures and secure improved ventilation where ventilation is required and obtain lightness with strength.

Further objects of the invention will hereinafter appear; and to these ends the invention consists of a sheet-metal construction for carrying out the above objects embodying the features of construction, combinations of elements, and arrangement of parts having the general mode of operation substantially as hereinafter fully described and claimed in this specification and shown in the accompanying drawings, in which—

Figure 1 is a front view of a locker-door embodying the invention. Fig. 2 is a vertical sectional view of the locker-door on the line $x-x$ of Fig. 1. Fig. 3 is a horizontal sectional view on the line $y-y$ of Fig. 1. Fig. 4 is a sectional plan view of the whole locker. Fig. 5 is an elevation of the back of the locker. Fig. 6 is an elevation of the end of the locker.

Referring to the drawings, A represents the uprights for the door, which are preferably of sheet metal bent into the required shape. The door is adapted to be hinged to the flange B or otherwise secured between the uprights. Over the door is preferably arranged a sheet-metal frame C. The sheet-metal door comprises the panel D, preferably having sheet-metal frames or raised portions E at each side and a reinforcement F at the top. The panel D in this instance consists of a sheet of metal having integral parts G pressed out beyond the plane of the sheet. In order to form these parts or projections, the sheet is slit as desired, in this instance two rows of horizontal slits being formed, and the metal immediately adjacent the slits is then forced out-

ward beyond the plane of the sheet. In the figures the slits are formed along the edges H, so that when the metal is forced outward curved pockets J are provided. In constructing the door the panel is placed with the pockets J pointing downward, and thus covering the openings K beneath them. 60

In forming the pockets J the metal of the pocket is somewhat stretched or drawn in order to make the loop projecting beyond the plane of the original sheet of metal.

In Figs. 4, 5, and 6 the whole locker is illustrated, showing how the invention is applied to both the back of the locker and one side, as well as the door. The back and sides of the locker comprise sheets of metal having the same construction described in connection with the door-panel.

According to this invention it will be seen that the locker-door is provided with vent-openings K for ventilation, and as the pockets extend over the openings and shield them 75 dust is shed therefrom, and the outside of the doors may be washed without the water entering the openings K. The pockets J also shed the wash-water.

By reason of this construction great 80 strength is added to the door, and it is at the same time very light.

Obviously some features of this invention may be used without others and the invention may be embodied in widely-varying 85 forms.

Therefore, without limiting the invention to the devices shown and described, and without enumerating equivalents, I claim, and desire to obtain by Letters Patent, the 90 following:

1. A sheet-metal locker provided with pockets pressed outwardly beyond the plane of the body and all extending downwardly over openings beneath said pockets or shields. 95

2. A sheet-metal locker having horizontal slits in pairs, the metal between the pairs of slits being forced outward beyond the plane of the sheet to form shields or pockets covering the openings beneath, all said shields extending downward.

3. A sheet-metal locker having portions integral therewith and forced outwardly beyond the plane of the sheet and all extending downwardly to form shields for the openings beneath. 105

4. A sheet-metal locker comprising the sides, back and door, the back and door having pockets pressed outwardly beyond the plane of the body and all extending downwardly over openings beneath said pockets.

5. A sheet-metal locker comprising the sides, back and a swinging door, in which one side, the back and the swinging door are provided with pockets pressed outwardly beyond the plane of the body and all extend-

ing downwardly over openings beneath said pockets.

In testimony whereof I have signed this specification in the presence of two subscribing witnesses:

PETER M. WEGE.

Witnesses:

H. E. WHITE,

H. T. SMITH.
